LIFTING JACK

Millard B. Lucker, St. Joseph, Mich., assignor to
 Auto Specialties Manufacturing Co., St. Joseph,
 Mich., a corporation of Michigan

Application April 17, 1936, Serial No. 74,969

14 Claims. (Cl. 254—106)

This invention relates to lifting jacks, and more particularly to a jack of the friction collar type especially adapted for use with automotive vehicles and the like.

It is an object of the invention to provide a lifting jack of the friction grip type which is of improved and simplified construction. In accordance with the invention the jack parts can be more easily made and assembled, thus insuring lower cost and facility of production. More specifically, the invention in one of its phases provides a jack body which surrounds the central shaft, of individual parts which may be readily formed and assembled. These body parts may be either cast or stamped from sheet metal.

A further object is to provide a new and simplified arrangement for resiliently urging the actuating clamp into normal uncanted position.

It is a still further and important object of the invention to provide a lifting jack of the friction grip type which has improved operating characteristics, which is rapid in placement, load contacting, and load raising and releasing, and yet which insures a maximum of safety at all times. In accordance with the invention a load engaging member or saddle is provided which is adjustable to accommodate the position of the load to be raised. This member, together with the compactness of the jack as a whole and the speed with which the lifting body may be raised along the spindle, insures speedy jack placement and load contacting. The load engaging member also aids in retaining the jack body parts in assembled position. Means are also provided for insuring that the lowering of the jack may be rapid but positively and accurately controlled. The lowering or release means is simple and fast and yet insures absolute safety in that the lowering movement is always under positive and accurate control. More specifically in one form of the invention the release is controlled by an invariably positioned removable elongated bar, and in another form by means of an adjustable screw.

Other objects and advantages of the invention will be apparent from the following description when taken in connection with the accompanying drawings which illustrate certain preferred embodiments of the invention.

In the drawings, wherein like reference numerals refer to like parts throughout:

Figure 1 is an elevational view showing a lifting jack constructed in accordance with one form of the invention.

Figure 2 is a partial longitudinal sectional view of the jack of Figure 1 taken along the line 2—2 of Figure 3.

Figure 3 is also a sectional view but along the line 3—3 of Figure 1.

Figure 4 is a transverse sectional view taken along the line 4—4 of Figure 1.

Figure 5 is a view similar to Figure 2 but showing the actuating clamp in operated position.

Figure 6 is an exploded view more particularly illustrating the jack body of metal castings.

Figure 7 is a detail perspective of the load engaging saddle.

Figure 8 is a detail perspective of the holding clamp.

Figure 9 is a detail perspective of the actuating clamp.

Figure 10 is an exploded view showing the jack body parts as made from stamped sheet metal.

Figure 11 illustrates a modification of the invention wherein the release of the holding clamp is effected by means of an adjustable screw.

Figure 12 is a cut-away view of the device of Figure 11 taken along the line 12—12 thereof.

This application is a continuation-in-part of my prior copending application Serial No. 43,752, filed October 5, 1935, for Lifting jack.

Referring first to Figures 1 to 9 inclusive, it will be seen that this embodiment of the invention, shown for purposes of illustration, comprises a base 10 having an upstanding shaft 35 or standard 11 fixed thereto in any suitable manner as by means of a pin or the like. The standard 11 carries the lifting body 12 of the jack which is adapted for sliding movement therewith. In this form of the invention the lifting body 40 is composed of two metal castings 13 and 14 as best seen in Figure 6. These two castings are secured together at their bottoms by means of screws or rivets 15 which pass through holes in flanges formed at the bottoms of the castings. 45 The body parts are secured together at the top by means of the load engaging saddle 16 which embraces both body parts and which is held against removal from the body by means of a beaded flange 17 formed at the extreme upper 50 portion of the body castings. The saddle is retained against movement downwardly along the body members by means of the flange 18 formed thereon. The saddle is rotatable about the body so that its object or load engaging portion 19 55

may be readily moved to the desired load engaging position. The load, as illustrated, is a portion 14 of the bumper of an automotive vehicle, as the lifting jack of the present invention is particularly adapted for use in such connection. It is to be understood, however, that the jack may be applied to other portions of a vehicle or to other types of loads to be raised.

A housing 20 formed at the lower portion of the lifting body carries the actuating clamp 21 and the holding clamp 22 of the jack operating mechanism. As will be seen by reference to Figure 9, the actuating clamp has formed on the upper face thereof a lug 23 adapted for engagement with the body housing when the actuating clamp is in its upper normal position as shown in Figure 2. A pair of diametrically disposed lugs 24 are also formed on the upper face of the actuating clamp to which the lower ends of a pair of springs 25 are secured. The upper ends of the springs are anchored to projections 26 formed on the lifting body members. The operating lever 27 for the jack is pivoted by means of a pin 28 to the body members and has an operating portion 29 adapted for engagement with the top of the actuating clamp at a point diametrically spaced from the projection 23.

The holding clamp 22 has an extending portion 30 journaled in an opening 31 formed in the housing 20 as best seen in Figure 3. The holding clamp is also formed with a projection 32 adapted to extend through an opening 33 formed in the housing diametrically to the opening 31. A compression spring 34 arranged between a cup 35 formed on the lower side of the projection 32 and a cup 36 formed on the body casting normally holds the holding clamp in canted position. The housing 20 also carries an integral projection 37 which, as best seen in Figure 1, is upwardly and laterally spaced from the projection 32 of the holding clamp. The release bar 38, by which the jack is lowered, is adapted for cooperation on its upper face with the housing lug 37 and on its lower face with the projection 32 of the holding clamp as will be best understood by reference to Figure 1. Lug 37 forms a fulcrum for the bar.

In assembling the jack the two parts 13 and 14 of the lifting body 12 are brought into operative juxtaposition with the holding clamp 22 and the actuating clamp 21 arranged within their housing portions. The springs 25, which have been previously secured to the actuating clamp, are connected to the projections 26 on the body parts, and the springs are stretched slightly as the actuating clamp is forced downwardly into the housing portion 20 of the body. With the body parts thus positioned, the screws or rivets 15 may be inserted to secure the lower body portions together. The load engaging saddle 16 is then slipped over the upper portions of the body parts into engagement with the flange 18 after which the flange 17 may be beaded over the top of the saddle to secure it in position. The saddle in turn secures the upper portions of the body members together. The compression spring 34 and the operating lever 27 may then be mounted in position after which, upon compression of spring 34, the entire movable lifting portion of the jack may be moved downwardly about the standard 11. The standard shaft insures that the springs 25 will not slip off of the lugs 26.

In operation, the compression spring 34 normally cant the holding clamp as shown in Fig-

ure 3 whereby to cause the biting edges of its central opening to grip the standard 11 and prevent the lifting body 12 from downward movement along the standard. The actuating clamp 21 is held in its normal uncanted and upward position by the springs 25. As the end of the operating lever 27 is moved upwardly, as indicated by the arrow in Figure 2, its engaging portion 29 causes the actuating clamp 21 to cant to bring the biting edges of its central opening into tight engagement against the standard 11. As the movement of the operating lever is continued as indicated in Figure 5, the actuating clamp acts as a reaction base causing the entire lifting casting to move upwardly along the standard. The holding clamp does not prevent such upward movement, but moves upwardly with the body 12 and by reason of the spring 34 prevents any retrograde movement, thus holding the body in its new upward position. As the operating lever is returned to normal position, the springs 25 draw the actuating clamp into normal uncanted upward position. The operation may be repeated until the lifting body is brought up to the desired position. Prior to engagement with the load, the entire lifting body may be lifted by hand upwardly along the standard 11, without manipulation of the operating lever 27, the clamps 21 and 22 readily permitting this preliminary adjustment movement. The load engaging saddle member 16 may be readily revolved about the body whereby to bring its load engaging portion 19 into the desired operative position. These features insure speed of jack placement and load raising.

To release the lifting body, the release bar 38 is brought into position as shown in Figure 1 with its upper side in engagement with the housing lug 37 and its lower side in engagement with the projection 32 on the holding clamp. As the right end of the bar 38 is now lowered, as indicated by the arrow in Figure 1, the spring 34 will be compressed, allowing the holding clamp to release its grip upon the standard. Downward movement of the lifting body under the load causes a corresponding lowering of the left end of the release bar, and this results in the relief of downward pressure against the projection 32 of the holding clamp. The spring 34 thereupon causes the holding clamp to again grip the standard 11. In other words, the lifting body 12 can be lowered only at the same time that the right end of the release bar is being lowered. If movement of the operating end of the release bar is stopped, the downward movement of the lifting body also immediately stops. By this means the downward movement of the lifting body is under accurate and positive control at all times whereby to insure complete safety as well as ease of operation. It is to be noted that due to the positioning of the lug 37 with respect to the projection 32 of the holding clamp, the release bar 38 can only be operatively inserted in one position, that shown in Figure 1. So long as the release bar is introduced from the accessible side of the jack, adjacent the operating lever 27, it is impossible to improperly manipulate the bar. The release is rapid but positively controlled.

In Figure 10 the lifting body of the jack is shown as formed of two sheet metal stampings 40 and 41. These body members are of substantially the same shape as the cast body members 13 and 14 described in connection with the first illustrated embodiment of the invention, and the man-

ner of assembly and operation is the same. In the case of the stamped body members, the members will be provided with openings 42 through which pins corresponding to lugs 28 may be inserted. 5 Also, the flanges, such as 43, 44 and 45, and the body openings, such as 46 and 47, will in this instance be formed by bending and punching the metal, rather than by casting, as is well understood in the stamped sheet metal art. It is to be 10 noted that the body members, whether formed by casting or by stamping sheet metal, may be readily and easily produced. There are no difficult formations to be made. Thus the barrels 48 which house the springs 25, are merely of cylindrical formation which may be readily produced either in a casting or by sheet metal stamping. The assembly of the body parts and the operating mechanism may be effected with a minimum 15 number of operations whereby to minimize assembly costs.

In Figures 11 and 12 there is illustrated a modified means for securing the accurate and controlled lowering of the lifting body. In this instance the housing 20 of the lifting body carries a threaded boss 50 into which a release screw 51 is adapted to be threaded. The conical inner end 52 of the release screw engages the projection 32 of the holding clamp adjacent its upper face as indicated in Figure 11. As the release screw is rotated by means of a suitable operating tool, its conical inner end forces the projection of the holding clamp downwardly against the action of compression spring 36 whereby to release the holding clamp from the standard 11. 25 In this instance the degree to which the holding clamp is released will be proportional to the degree of rotation imparted to the release screw. Accordingly the rate at which the lifting body will be lowered under any given load will likewise be proportional to the degree of rotation imparted to the release screw, and the rate of descent will be uniform so long as the adjustment of the release screw is not changed. By this release means the rate of load descent can be accurately and positively controlled as in the case 30 of the first described embodiment of the invention. Claims more particularly directed to the structure of Figs. 11 and 12 are presented in my copending application, Serial No. 299,338, filed 35 October 13, 1939. Also, claims to other features of the structure disclosed, but not herein claimed, are presented in the aforementioned companion application, Serial No. 43,752, filed October 5, 1935.

It is obvious that various modifications may be 40 made in the specific embodiments of the invention shown for the purpose of illustration. Accordingly the invention is not to be limited to the precise constructions shown and described, but only as indicated in the following claims.

60 The invention is hereby claimed as follows:

1. In a lifting jack of the friction grip type, a base, an upstanding shaft operatively carried by the base, a lifting body composed of individual pieces slidably along the axis of said shaft, a housing formed in said body, actuating and holding clamps in said housing embracing the shaft, and a load engaging member carried by the lifting body, said load engaging member embracing a plurality of said pieces and being rotatably adjustable thereon.
2. In a lifting jack of the friction grip type, a base, an upstanding shaft operatively carried by the base, an elongated lifting body comprising a plurality of individual elongated sheet metal pieces collectively encircling said shaft and slid-

able therealong, friction gripping means arranged within said body, means for securing said pieces together at the top and bottom thereof, and means on at least one of said pieces forming a pivotal engagement for said friction gripping 5 means.

3. In a lifting jack of the friction grip type, a base, an upstanding shaft operatively carried by the base, a lifting body including a pair of individual body pieces secured together and slidably longitudinally of the shaft, a housing formed in said body, a friction clamp in said housing embracing the shaft, and a pair of springs secured to said clamp for holding it in position, each of said springs being anchored to one of said body 10 pieces.

4. In a lifting jack of the friction grip type, a base, an upstanding shaft operatively carried by the base, a lifting body embracing said shaft and slidably therealong, a housing formed in said body, a friction clamp in said housing embracing the shaft, and a pair of springs secured to said clamp at diametrically spaced points and anchored to said body for holding the clamp in 15 position within the housing.

5. In a lifting jack of the friction grip type, a shaft, a body embracing the shaft, a housing formed in said body, a friction clamp mounted in said housing embracing the shaft, and a pair of springs connected to said clamp at diametrical- 20 30 spaced points thereon and anchored to the body for holding the clamp in position within said housing.

6. In a lifting jack of the friction grip type, an elongated shaft, a body embracing said shaft, said body and shaft being relatively slidably, a holding clamp carried by the body embracing the shaft and adapted to be normally canted to grip the shaft, whereby to hold the body and shaft against relative movement in one direction, a radially ex- 35 40 tending projection on the holding clamp, and a lug formed on said body, said lug being laterally displaced with respect to the projection whereby to facilitate the proper positioning of a release bar adapted for application to the projection and 45 fulcrum movement upon said lug.

7. In a lifting jack of the friction grip type, an elongated shaft, a body on said shaft, said shaft and body being relatively movable, a housing formed in the body, a locking clamp arranged 50 in the housing embracing the shaft for locking the body and shaft against movement in one direction, a projection on said clamp extending radially therefrom, resilient means for normally urging the clamp so as to urge the projection upwardly to cant the clamp in locking position, and a lug formed on the body, said lug being spaced laterally and upwardly from said projection whereby to facilitate the control of a release bar 55 adapted for application to the projection and ful- 60 crum movement upon the lug.

8. In a lifting jack of the friction grip type, a shaft, a body encircling the shaft, a housing formed in said body, an actuating friction clamp mounted in said housing embracing the shaft, a 65 pair of springs connected to said clamp at diametrically spaced points thereon and anchored to the body for holding the clamp in position within said housing, a holding friction clamp also mounted within said housing and embracing the 70 shaft, a spring engageable with the holding clamp and with the housing for normally holding said clamp in canted friction gripping engagement upon the shaft, and release means engageable with the housing and the holding clamp for mov- 75

ing the latter to uncanted position against the action of its spring.

9. In a lifting jack of the friction grip type, a base, an upstanding shaft operatively carried by the base, an elongated lifting body comprising a plurality of individual elongated body pieces collectively encircling said shaft and slidably therealong, said body pieces forming a substantially enclosed housing, friction gripping means arranged within said housing, and means for securing said body pieces together at the top and bottom thereof.

10. In a lifting jack, a base, an upstanding shaft operatively carried by the base, a lifting body slidably along and rotatable about said shaft, friction gripping means carried within the body for frictionally gripping the body to the shaft, a laterally extending member pivoted to the body and adapted on pivoted movement to operate said friction gripping means, a load engaging member mounted on said lifting body, said load engaging member being shiftable relative to the lifting body about the axis of the shaft, whereby the lifting body may be shifted about the axis of the shaft to position the laterally projecting member in any desired plane of operation without axial displacement of the lifting body relative to the shaft, and the load engaging member may be independently shifted about the axis of the shaft for engagement with a load to be raised.

11. In a lifting jack of the friction grip type, an elongated shaft, a body embracing said shaft, said body and shaft being relatively slidably, a holding clamp carried by the body and embracing the shaft and adapted to be normally canted to grip the shaft, whereby to hold the body and shaft against relative movement in one direction,

a radially extending engagement surface on the holding clamp, and a cooperating engagement surface formed on said body, said body engagement surface being laterally displaced with respect to the clamp engagement surface whereby to facilitate the proper positioning of a release bar adapted for application to the clamp engagement surface and fulcrum movement upon said body engagement surface.

12. A vehicle jack comprising a supporting column, a split tubular member mounted on said column for actuation therealong, a vehicle supporting portion carried by said tubular member, said vehicle supporting portion comprising a rigid sleeve telescoping with said split tube and having at least one receiving ledge portion defined thereby to provide a seat, said sleeve comprising a ferrule for reinforcing said split tube, and means projecting from said tubular member mounted on said supporting column for providing a seat for said sleeve.

13. In a lifting jack of the friction grip type, a base, an upstanding shaft operatively carried by the base, an elongated lifting body comprising a plurality of individual elongated body pieces collectively encircling said shaft and slidably therealong, friction gripping means arranged within said body, means for securing said pieces together at the top and bottom thereof, and means on at least one of said pieces forming a pivotal engagement for said friction gripping means.

14. A vehicle jack structure as defined in claim 12 wherein the rigid sleeve is rotatably mounted upon the split tube, whereby to be rotatably adjustably positioned thereon.
